UNITED STATES PATENT OFFICE.

FREDERICK AUGUSTUS PURCHAS, OF McGRAW, NEW YORK, ASSIGNOR TO ONEIDA COMMUNITY, LIMITED, OF ONEIDA, NEW YORK, A CORPORATION OF NEW YORK.

TRAY OR THE LIKE.

Application filed May 5, 1925. Serial No. 28,065.

This invention relates to improvements in trays or the like.

The object of the invention is to provide a tray or the like equipped with retaining means, detachably connected with the tray, for receiving and holding, in proper position during display and transit, articles of silver or silver-plate or other material which the tray is to carry or contain for shipment or display.

In the accompanying drawings—

Fig. 1 is a perspective view of a tray embodying the improvements of the present invention in their preferred form, the tray being shown as carrying spoons in position for display;

Fig. 2 is a longitudinal section thereof on the line 2—2 of Fig. 1;

Fig. 3 is a transverse section thereof on the line 3—3 of Fig. 1, the spoons, however, being shown in position for shipment;

Figs. 4 and 5 are edge views of two forms of retainer for receiving and holding the spoons or other articles which the tray is to carry and display.

Referring to Figs. 1—3, A represents the bottom of the tray, B its side border sections, C its end border sections, and D an easel portion which may be secured to the tray, if desired.

In the construction shown in these figures the bottom A and side and end border sections B, C, are formed from a single blank of cardboard or other suitable material. The border sections may have a paper covering P.

A retainer E or E' (Figs. 4, 5) is provided for the articles to be carried and displayed on the tray, consisting of a strip of spring metal connected at its opposite ends with the tray as by having its ends enter openings o provided in the side border sections B.

The strip E of Figures 3 and 4 is bent at suitable intervals to provide recesses e on its under side and smaller recesses e' on its upper side. Each of the lower recesses e is of a width suitable for the reception of a package of spoons or other articles (as shown in Fig. 3) while each of the upper recesses e' is of a width suitable for receiving the spoons (when unpacked) and displaying them in the tray (as shown in Fig. 1). The strip E is bowed or bent downwardly, as shown in Fig. 4, and the walls of each re-

cess e' are so spaced that in this position they will grip the articles in the recess and thus hold them securely in proper position for display. To release the articles from this gripping engagement so that they may be readily removed from the recess all that it is necessary to do is to bend the spring E at its centre and thereby spread the walls of the recesses apart.

The retainer E' of Fig. 5 differs from that of Figure 4 in that it is bowed or bent upwardly. In its normal or upwardly bowed position the walls of its recesses e' are spread apart and the articles carried in the recesses are therefore loose and may readily be removed, but when pressure is applied to the spring E', as by the application of a cover when the tray is stored or shipped, it is depressed and the walls of the recesses e' grip the articles and resist their movement therein.

What is claimed is:

1. The combination with a receptacle, of a resilient article-retaining strip therein and bendable to and from the bottom thereof, said strip being provided with recesses on its under side for retaining the articles in packaged condition for shipment and with recesses on its upper side for retaining and displaying the same articles in unpackaged condition, said strip being normally bowed in one direction relatively to the bottom of the receptacle and having the walls of its upper recesses so spaced that in one position of the strip they will grip and in the other position thereof release the articles therein.

2. The combination with a receptacle, of a resilient article-retaining strip therein and bendable to and from the bottom thereof, said strip being provided with recesses on its under side for retaining the articles in packaged condition for shipment and with recesses on its upper side for retaining and displaying the same articles in unpackaged condition, said strip being normally bowed toward the bottom of the receptacle and the walls of its upper recesses so spaced that in that position of the strip they will grip and in the other position thereof release the articles therein.

In testimony whereof, I have hereunto set my hand.

FREDERICK AUGUSTUS PURCHAS.
